UNITED STATES PATENT OFFICE.

ALBERT R. HUGHES, OF THOMAS, OKLAHOMA.

PRUNING-SHEARS.

1,072,232.

Specification of Letters Patent. Patented Sept. 2, 1913.

Application filed May 2, 1911. Serial No. 624,574.

To all whom it may concern:

Be it known that I, ALBERT R. HUGHES, a citizen of the United States, residing at Thomas, in the county of Custer and State 5 of Oklahoma, have invented a new and useful Pruning-Shears, of which the following is a specification.

This invention relates to improvements in pruning shears of that type wherein one 10 blade is stationary and the other blade is movable through a manually actuated lever.

The invention has for its object, among other things, to secure a direct and efficient cutting action of the severing blades.

15 A further object is to simplify the construction of the parts and their arrangement, and to provide for facility in actuating the device.

A still further object is to promote the 20 general utility of the contrivance.

A still further object is to carry out the aforesaid ends in a simple, inexpensive and effective manner.

The invention consists of certain instruments 25 and features substantially as hereinafter fully described and defined by the claims.

In the accompanying drawings illustrating the preferred embodiment of my invention 30 wherein it will be understood that various changes and modifications as relates to the details of the construction and arrangement of the parts may be made without departing from the spirit of the invention;—

35 Figure 1 is a side elevation of my pruning shears, shown in full lines in closed or inoperative position and in dotted lines in open position. Fig. 2 is a cross-section thereof, produced through the head of blade- 40 equipped part of the shears, including the ax and saw members said section being designated by the line $x-x$ in Fig. 1. Fig. 3 is a broken reversed side elevation of the same disclosing more especially the saw hold- 45 ing or set screw.

In practising my invention, I provide a suitable handled or carrying member 1 for, and upon which is mounted or supported the cutting or severing members as presently 50 disclosed, and to this carrying or handled member is pivoted a lever 2 adapted to be suitably or manually actuated.

A movable severing member or blade 3 is 55 slidably supported in position in any suitable manner, as between guides 4 secured

to the member 1, or such guides may be cast with the latter. The blade 3 is preferably rectangular in general outline, having longitudinal contracted lateral edge portions received under the guides 4, the lower or 60 cutting edge of said blade being beveled off to form such edges, which coöperate with an oppositely beveled cutting edge of a second blade or severing member 5 suitably secured or held in stationary position upon 65 the lower edge of a laterally opening recess 6^a formed in the member 1. Any ordinary means, as set screws, or the like, may be employed in connection with the suitably-seating of the blade 5 in the member 1, for re- 70 tention and adjustment of the blade in position with respect to the blade 3.

Suitable lever and link connection is effected between the movable blade 3 and the lever 2, the lever of said connection, designated at 6, being centrally fulcrumed in position and having one end provided with a slot 7, or bifurcated, to receive one end of the link, designated as 8, said link being pivoted at its ends to said levers, respectively. The opposite end of the lever 6 has a slot 9 therein receiving a headed stud or screw 10 outstanding from the movable blade, about centrally thereof, the connection thus formed between said lever and 80 blade conforming to the differential movement between said parts occurring when the same are actuated. The lever 2, it will be noted has at its upper end a lateral upwardly and diagonally extended arm or ex- 85 tension as 11 beyond its pivotal point or fulcrum, the connection between the link 8 and said lever being effected at this point, in order to suitably actuate the movable blade through the lever 6 and said link in deliver- 90 ing a movement to said blade perpendicular to the actuating movement of the lever 2, as required to impart the requisite cutting movement to said blade, as will be readily understood.

At the upper end of the handled member 1 and extending laterally therefrom, is what may be termed a three-edged ax-member 12, and within a suitable inclosing space 13 provided in the member 1, is a saw blade 105 member 14 suitably held in projected or retracted position by a set screw 15, said space having a closure 16 suitably held in place, and which ax-member and saw-blade member may serve for general utility purposes, 110

particularly for severing or chopping off limbs which may not be conveniently accessible or severable in the use of the bladed portion of the implement, and others which may require for their pruning the action of a saw.

In operation, it will be noted that the handled carrying member 1 being suitably grasped and manipulated to properly dispose its head or upper end and the severing blades with respect to the limb or branch of the tree it is desired to engage, and by causing said limb or branch to enter the laterally opening recess of said head, and that, by now suitably actuating the lever 2, the movable blade will be forcibly moved into contact with the limb and accordingly contact with the stationary blade to effect the severing or pruning of the limb.

It is believed that, from the foregoing disclosure, taken in connection with the illustration or drawing, the advantages and benefits of my invention have been made fully apparent, it also being very simple in construction, formed of few parts, readily operated, effective in action and for its intended purpose, and inexpensive of manufacture.

What is claimed is;

A pruning tool comprising a handle provided at its outer end with an outstanding terminal arm and provided between its ends with an outstanding intermediate arm; a blade fixed on the intermediate arm; a blade mounted for vertical movement on the terminal arm and adapted to move downwardly in a straight line parallel to the handle to engage the upper edge of a branch thereby to prevent a clamping of said blade by the branch when partially severed; an actuating lever fulcrumed intermediate its ends upon the handle and adapted at one end to move into parallelism with the handle; a second lever fulcrumed intermediate its ends on the handle and pivoted at one end loosely, directly to the movable blade; and a link forming a connection between the other ends of both levers.

In testimony that I claim the foregoing as my own, I have hereto affixed my signature in the presence of two witnesses.

ALBERT R. HUGHES.
